CLAIM

The ornamental design for a water bottle, as shown and described.

DESCRIPTION

FIG. 1 is a perspective view of an embodiment of a water bottle showing our new design;

FIG. 2 is a front elevation view thereof, the side elevation views are a mirror image of the front elevation view;

FIG. 3 is a top view thereof;

FIG. 4 is the first image in a sequence for a water bottle with animated interface showing our new design;

FIG. 5 is the second image thereof;

FIG. 6 is the third image thereof;

FIG. 7 is the fourth image thereof;

FIG. 8 is the fifth image thereof;

FIG. 9 is the sixth image thereof;

FIG. 10 is a first image of a sequence for a water bottle with animated interface showing our new design; and,

FIG. 11 is the second image thereof.

The appearance of the animated graphical user interface sequentially transitions between the images shown in FIGS. 4-11. The process or period in which one image transitions to another forms no part of the claimed design.

The dashed lines in the drawings represent unclaimed boundary lines and form no part of the claimed design. The stippling in the drawings indicate a contrast in appearance.
